CLAIM

The ornamental design for a toner cartridge as shown and described.

DESCRIPTION

FIG. 1 is a first perspective view of front, top and right side of a toner cartridge showing my new design;

FIG. 2 is a second perspective view of front, top and left side thereof;

FIG. 3 is a third perspective view of rear, top and right side thereof;

FIG. 4 is a fourth perspective view of rear, top and left side thereof;

FIG. 5 is a fifth perspective view of front, bottom and left side thereof;

FIG. 6 is a sixth perspective view of rear, bottom and left side thereof;

FIG. 7 is a seventh perspective view of front, bottom and right side thereof;

FIG. 8 is a eighth perspective view of rear, bottom and right side thereof;

FIG. 9 is a front view thereof;

FIG. 10 is a rear view thereof;

FIG. 11 is a left side view thereof;

FIG. 12 is a right side view thereof;

FIG. 13 is a top plan view thereof; and,

FIG. 14 is a bottom view thereof.

The broken lines shown in the drawings represent portions of the toner cartridge that form no part of the claimed design.

1 Claim, 14 Drawing Sheets
